UNITED STATES PATENT OFFICE.

WILLARD F. MEYERS, OF LONG ISLAND CITY, NEW YORK.

STONE-SAWING MACHINE.

1,017,784.

Specification of Letters Patent. Patented Feb. 20, 1912.

Application filed July 31, 1909. Serial No. 510,539.

To all whom it may concern:

Be it known that I, WILLARD F. MEYERS, a citizen of the United States, residing at Long Island City, borough of Queens, city 5 of New York, in the county of Queens and State of New York, have invented a certain new and useful Improvement in Stone-Sawing Machines, of which the following is a specification, reference being had therein to 10 the accompanying drawings, forming part thereof.

My invention relates to stone sawing machines, particularly to cutting off machines for stone, and the objects of my invention 15 are to render the machine in some respects automatic, so that it requires less attention, to increase the capacity of the machine, both as to quantity of work and size of work that can be handled, and to increase the facility 20 of adjustment of the work and of the machine.

Other objects and advantages will appear from the following description.

My invention includes double adjustable 25 work-supporting extensions for the work-supporting table.

My invention also includes means facilitating the shifting of the work on the table.

My invention also includes means for adjusting the cutting off saw independently of 30 its supporting frame and means for actuating the saw from an outside source of power without interfering with its adjustment, such means including a shaft hanger arranged 35 to move in unity with the saw-supporting frame.

My invention also includes other advantageous features and several details of construction and combinations of parts, as will 40 hereinafter appear.

I shall now describe my invention with reference to the accompanying drawings and shall thereafter point out my invention in claims.

Figure 1 is a plan view, with portions broken away, of a machine embodying my invention. Fig. 2 is a plan view, on a reduced scale, of the work-supporting table. Fig. 3 is a side elevation, partly in section, 45 as viewed from the right of Fig. 1. Fig. 4 is a section on a plane indicated by line of section 4—4 of Figs. 1 and 5 as viewed from the right, with parts omitted, and shows a detail of the feed mechanism. Fig. 5 is a 50 vertical section on a plane indicated by line of section 5—5 of Fig. 3 as viewed from

the left. Fig. 6 is an enlarged plan view of the carriage, portions of the carriage-supporting frame being also shown. Fig. 7 is an elevation of what is shown in Fig. 6 as 60 viewed from below, parts being omitted. Fig. 8 is a view similar to Fig. 7 with other parts omitted and showing a different position of adjustment. Fig. 9 is an elevation of what is shown in Fig. 6 as viewed from 65 above and with parts omitted. Fig. 10 is a vertical section on a plane indicated by line of section 10—10 of Fig. 6 as viewed from the right. Fig. 11 is an enlarged detail plan view, showing portions of the mechanism for 70 facilitating the shifting of the work on the table. Fig. 12 is an enlarged elevation of what is shown in Fig. 11 as viewed from below, a portion of the work-supporting table also being shown. Fig. 13 is an end elevation 75 of an adjustable shaft hanger forming a part of my invention. Fig. 14 is a side elevation of what is shown in Fig. 13 as viewed from the right. Fig. 15 is a plan view, with portions broken away, of a modified construction in which the work-supporting table is equipped with a work-carrying device. Fig. 16 is an elevation of what is 80 shown in Fig. 15. Fig. 17 is a vertical section on an enlarged scale on a plane indicated by line of section 17—17 of Fig. 15, 85 portions being broken away.

The illustrated embodiment of my invention comprises a work-supporting table 11, on which is mounted a vertically adjustable 90 frame 12 supported on split sleeves 13 slideable on posts or columns 14 and adapted to be retained in any desired position of vertical adjustment by clamping bolts 15. The frame 12 may be raised or lowered to different 95 positions of vertical adjustment by lifting screws 16 journaled on the table 11 and having screw-threaded engagement with lifting nuts 17 carried by opposite ends of the frame 12. The lifting screws 16 are 100 of the same pitch and are connected together to be operated in unison in the proper direction and at the same rate, so that the frame 12 may be adjusted up and down with an equal and parallel movement of all its 105 portions. The lifting screws 16 are adapted to be actuated in this manner by a transverse shaft 18 passing beneath the table 11 and journaled thereon and geared to the lifting screws 16 by bevel gears, as shown in 110 the drawings. The transverse shaft 18 is shown as provided with a squared end por-

tion 19 and vertical adjustment of the frame 12 may be manually effected by the application of a crank or wrench to this squared portion.

- 5 A tool-supporting carriage or saw carriage 20 is mounted to slide longitudinally of the horizontal cross frame 12 and is held in place and guided on the frame by dovetail gibbs on the carriage, which engage with 10 dovetail ways on the frame, as shown in the drawings, most clearly in Fig. 10. A rotary cutting-off saw 21 is fixed on a saw shaft 22 journaled in a saw-support comprising segmental end plates 23 and 24 fixed on a connecting rock shaft 25, pivoted on the saw carriage 20. This swinging saw-support permits the saw 21 to be raised and lowered relatively to the table 11 independently of raising and lowering the frame 12, thereby 15 providing greater convenience and facility in adjusting the saw 21 to any work supported on the table 11. To retain the saw 21 in different positions of vertical adjustment relatively to the carriage 20, the end plates 20 23 and 24 are provided with arcuate slots, as shown in the drawings, and are adapted to be clamped in place by clamp bolts 26 passing through these slots and engaging the carriage 20. For the sake of increased 25 strength, the clamp bolts 26 are placed out of radial line at each end, being shown as in quadrature with the rock shaft 25, and the curved slots in the plates 23 and 24 are formed accordingly. When the clamp bolts 30 26 are loosened, the saw 21 may be conveniently adjusted relatively to the carriage 20 by a worm 27 engaging gear teeth formed in the edge of the segmental plate 24, which constitutes a worm wheel. The worm 27 is 35 carried by a squared shaft 28 journaled on the carriage 20 and to which a wrench or crank may be applied to manually effect the desired adjustment. The two extremes of 40 vertical adjustment of the saw 21 relatively to the carriage 20 are shown in Figs. 7 and 45 8, Fig. 7 showing the highest adjustment and Fig. 8 the lowest. The means for actuating the saw 21 comprise a spur gear 29 fixed on the saw shaft 22 and in mesh with 50 a larger spur gear 30 carried by a sleeve 31 loosely mounted on the rock shaft 25 and shown as extending into bearings in the carriage 20, the sleeve 31 having a belt pulley 32 fixed thereon. The rotative speed of the 55 saw 21 may be varied by transposing the gears 29 and 30 or by substituting for these gears other gears of different relative diameters.
- 60 The saw 21 lies in planes substantially parallel with the length of the frame 12 and means are provided for feeding the carriage 20 along the ways of the transverse frame 12 to feed the saw 21 transversely of the table 11, the feed movement of the carriage 65 20 being automatically reversed to return

the saw to the starting point, at which point the return movement of the carriage is automatically stopped. These means comprise a feed screw 33 journaled near its ends on the frame 12 and having screw-threaded engagement with a nut 34 carried by the carriage 20. To impart the feed movement to the feed screw 33, a worm wheel or screw gear 35 is loosely mounted on one end of the feed screw 33 and is adapted to be rotatively connected therewith by a toothed clutch member 36 splined on the screw shaft 33, as shown in the drawings, the worm wheel 35 being shown as forming the other clutch member co-operative with the clutch member 36. The worm wheel 35 is rotated by a worm 37 carried by a feed shaft 38 journaled on the frame 12. To impart the return movement to the feed screw 33, a bevel gear 39 is loosely mounted on the other end of the screw 33 and is adapted to be rotatively connected therewith by a toothed clutch member 40 splined on the screw shaft 33, as shown in the drawings, and co-operative with the bevel gear 39, which constitutes also a clutch member. The bevel gear 39 is rotated by another bevel gear 41 carried by a carriage return shaft 42 journaled on the frame 12. The feed shaft 38 and the return shaft 42 are shown as geared together 95 for concurrent rotation by a belt 43 engaging cone pulleys 44 and 45 fixed on the shafts 38 and 42, respectively, the cone pulleys enabling changes in the relative rates of speed of the feed movement and of the return movement of the saw-supporting carriage 20, the return movement, however, always being more rapid than the feed movement because of the fact that for the return movement the screw 33 is driven by 100 the bevel gears 39 and 41, while for the feed movement the feed screw 33 is driven by the worm gears 35 and 37, which transmit a much slower rate of rotation. The connections are such as to rotate the worm 105 wheel 35 and the bevel gear 39 in opposite directions for transmitting to the screw 33 the feed movement and the return movement, respectively.

110 The clutch members 36 and 40 are connected together to be actuated concurrently, so that when the clutch member 36 is connected with the worm wheel 35, the clutch member 40 will be disconnected from the bevel gear 39, and vice versa. The means for connecting together and actuating the clutch members 36 and 40 include substantially parallel levers 46 and 47, pivoted on the frame 12 and having a pivotal connection with the clutch members 36 and 40, respectively, as shown in the drawings. The levers 46 and 47 extend upward and terminate in handle portions and are connected together by a connecting rod or link rod 48. For the determination of the feed movement 115 120 125 130

and of the return movement, respectively, collars 49 and 50 are shown as adjustably fixed on the rod 48 by set screws, and inward from the collar 49 toward the middle of the 5 rod 48 is a sliding collar 51 spaced from the collar 49 by a coiled thrust spring 52 surrounding the rod 48. The nut 34 of the carriage 20 carries a clutch-actuating toe 53, which slides on the rod 48 and is adapted to 10 engage with the collars 51 and 50.

In operation the feed movement is started by manipulating one of the levers 46 or 47 to bring the clutch member 36 into coöperative relation with the worm wheel 35, as 15 shown in Figs. 1 and 5. The feed screw 33, driven by the worm wheel 35, then feeds the carriage 20 along the frame 12 transversely of the table 11. When the traveling toe 53 comes in contact with the sliding collar 51, 20 the further feed movement of the carriage 20 compresses the spring 52 which acts as an energy-storing device and when this compression has become sufficient, the spring 52 acts on the fixed collar 49 to move the rod 25 48 longitudinally toward the left, as illustrated in Figs. 1 and 5 of the drawings, and the rod 48 actuates the levers 46 and 47, first, to disconnect the clutch member 36 from the worm wheel 35 and thereby stop 30 the feed movement of the carriage 20, and, next, as the movement of the rod 48 is continued by the spring 52, to connect the clutch member 40 with the bevel gear 39 and thereby cause a reverse movement or return 35 movement to be communicated to the carriage 20. As the return movement continues, the toe 53 comes in contact with the fixed collar or throw-out collar 50 and pushes the rod 48 in an opposite direction or toward the 40 right, as illustrated in Figs. 1 and 5, and throws out or disconnects the clutch member 40 from the bevel gear 39 and thereby brings the carriage to a stop, there being in this instance no spring or other device to continue 45 the movement of the rod 48. Upon the completion of its return movement, the carriage 20 will remain stationary until it is given a feed movement by the manipulation of one of the levers 46 or 47. The collars 49 and 50 50 may be adjusted along the rod 48 to cause the feed movement and the return movement of the carriage to cease at any desired point. 55

Driving means or actuating means in common are provided for the feed shaft 38 and 55 return shaft 42, and for the saw-actuating pulley 32. Such means include a main drive shaft 54 provided with a belt pulley 55 connected with the saw-actuating pulley 32 by a belt 56, and also provided with a cone pulley 57 connected by a belt 58 with a second cone pulley 59 fixed on the return shaft 42, which, as above noted, is connected with the feed shaft 38 by the belt 43. To permit of the vertical adjustment, as hereinbefore described, of the frame 12, carrying the pulleys 60

32 and 59, without interfering with the function of the belts 56 and 58, means are provided for raising and lowering or vertically adjusting the main shaft 54 in unity with the vertical adjustment of the frame 12. 70 To this end, the main shaft 54 is located substantially above, or vertically upward from, a median position of the carriage 20, as will appear by placing Fig. 13 of the drawings above Fig. 5, and Fig. 14 above Fig. 3, and the main shaft 54 is journaled in shaft hangers 60, which are guided and adapted to slide vertically on supporting brackets 61. To vertically adjust the hangers 60 in unity with the frame 12, vertical screws 62 are 80 journaled in the brackets 61 and have screw-threaded engagement with the hangers 60. At their lower ends the vertical screws 62 are geared by bevel gears, as shown in Figs. 13 and 14, to a screw-actuating shaft 63 journaled on the brackets 61 and carrying a sprocket wheel 64 which is connected by a chain 65 with a second sprocket wheel 66 carried by a short shaft 67 geared by bevel gears, as shown in Figs. 1 and 5, to the 90 transverse shaft 18, which, as above noted, actuates the lifting screws 16 for vertically adjusting the frame 12. From the above description it is evident that when the screws 16 are actuated to raise or lower the frame 95 20, the screws 62 will be also actuated to correspondingly raise or lower the shaft hangers 60, the various gears and screws having, of course, the proper relation one to another to produce these movements at uniform rates. 100 Because of the fact that by this arrangement the distances between the main shaft 54 and the shafts 25 and 42, respectively, are not varied by the vertical adjustment of the frame 12, no changes in the lengths of the 105 belts 56 and 58 are required for the vertical adjustment of the frame 12. However, the sliding feed movement and return movement of the carriage 20 produce slight variations in distance between the saw-actuating pulley 110 32 and the main shaft 54, and the effect of these variations is eliminated and the saw-actuating belt 56 kept tight by a take-up device or belt-tightener comprising an idler 68 carried by arms 69 pivoted on the main shaft 115 54 and pressed against the belt 56 by a weight 70 adjustable along a yoke arm 71 extending from the arms 69.

For actuating the entire machine, including both driving and feeding the saw 21, a 120 main driving pulley 72 is mounted on the main driving shaft 54 and is arranged to be connected therewith or disconnected therefrom at will by a lever 73 adapted to actuate a clutch of usual construction, as 125 indicated in the drawings.

The work is supported on the table 11, and to facilitate cutting the work at different desired angles slotted guide cleats 74 are provided and are held in place by clamp 130

bolts engaging usual T-slots in the table 11. The saw 21, as above described, is fed transversely of the table, but the saw and the table do not move relatively to each other 5 in a direction longitudinal of the table. After making a cut, the work is moved up longitudinally of the table to a new position relatively to the saw for making another cut. To facilitate this movement or 10 adjustment of the work, elevating rollers 75 are located in slots or openings extending transversely of the table 11 and normally lie slightly below the upper surface of the table and therefore out of contact with the work, which then rests on 15 the table, but these rollers may be elevated or raised above the surface of the table so that the work will be supported on the rollers and may therefore be moved with 20 ease longitudinally of the table and thereby adjusted relatively to the saw 21. The elevating rollers 75 are carried by levers 76 pivoted to the table 11 at the under side thereof and resting at their free ends on 25 cams 77 carried by cam shafts 78 journaled below the table and provided at one end with lever arms 79. All the lever arms 79 are connected together by a connecting bar 80 for actuating the cams 79 concurrently 30 to raise all of the rollers 75 at the same time. The bar 80 may be actuated either by a hand lever 81 pivoted at the side of the table 11 or by a treadle 82 connected to the bar 80 by a link 83 and bell crank 84. 35 A saw-receiving groove 85 is provided transversely of the upper surface of the table 11 and receives the cutting edge of the saw 21. The fact that the saw 21 extends into the groove 85 enables the work to be 40 completely cut through and severed by the saw, thereby producing smooth corners in the work. Because of the fact that the saw 21 moves only transversely of the table 11 and that there is no relative movement of 45 the saw and table longitudinally of the table, the groove 85 does not in any respect interfere with the operation of the saw. 50 Means are provided for increasing the work-supporting capacity of the work-supporting table 11 so that slabs of stone of large size and projecting beyond the ends 55 of the table can be handled. Such means comprise an extensible frame including side beams or side rails 86 and end work-supporting rollers 87, the ends of the beams or rails 86 being bent upwardly so that the rollers 87 are substantially on a level with the top of the table 11. The beams 86 are supported and guided by lower anti-friction 60 rollers 88 and upper anti-friction rollers 91, at the under side of the table 11, the lower rollers 88 being located at the under sides of the rails 86 adjacent to the ends of the table 11 and the upper rollers 91 being located 65 at the upper sides of the rails 86 in-

wardly from the lower rollers 88. This extensible frame is formed in two parts, one part at each end of the table, the two parts being united by slotted plates 89 overlapping the inner ends of the beams 86 of each part and adapted to be secured thereto by bolts 90. By loosening the bolts 90 the respective end parts of the frame may be used independently, and by tightening these bolts while the two parts of the frame are separated, the frame may be used alternately at opposite ends of the table 11, such frame forming an extension to the table capable of being drawn out at either end of the table, the rollers 87 facilitating the shifting or 70 adjustment of the work in the same manner as do the rollers 75. 75

In the modified construction illustrated in Figs. 15, 16 and 17 a slightly flexible sheet metal work carrier 92 is provided overlying the table 11 and supported thereon when the elevating rollers 75 are in lowered position and adapted to be supported on the elevating rollers 75 when such rollers are raised. In this construction the work is 80 moved longitudinally of the table 11 by moving the work carrier 92 over the elevating rollers 75. The work carrier 92 is also adapted to form a work-supporting extension for supporting work which extends beyond the end of the table 11, as indicated in 85 Figs. 15 and 16. Means are provided for moving the work support or work carrier 92 and for supporting the extending portion thereof. Such means comprise rails 93 similar to the rails 86, except that the rails 93 are provided at their lower edges with gear teeth forming a rack, as shown in Figs. 16 and 17. The rails 93 are supported and guided by the rollers 88 and 91 in substantially the same manner as are the rails 86. The rack teeth of the rails 93 are engaged 95 by pinions 94, located between the supporting rollers 88, which are shown as arranged in pairs, and these pinions are fixed on an actuating shaft 95 adapted to be actuated by a worm gear comprising a worm wheel 96 fixed on the shaft 95 and engaged by a worm 100 97 carried by a worm shaft 98 geared, by bevel gears as shown, to a short shaft 99 105 provided with a hand crank 100. 110

When the work carrier 92 is not employed the work is moved up to the saw directly by hand, but when the work carrier 92 is provided the work is shifted by turning the 120 crank 100. This work-carrying device further facilitates the shifting of heavy work. The extensible work-supporting frame comprising the rollers 87 and rails 86 and the work-carrying device comprising the carrier 125 92 and rails 93 may be interchangeably used in the same machine, according to convenience and the character of the work. The carrier sheet 92 is shown as cut away at one side to provide space for the guide cleats 74, 130

employed for lining up the work. This work carrying device may be employed at one or both ends of the table 11 and may cover more or less of the surface thereof as desired.

It is obvious that various modifications may be made in the construction shown and above particularly described within the principle and scope of my invention.

10 I claim:

1. A stone-sawing machine comprising a work-supporting table, a saw, means for supporting the saw in position to act on the work, means for actuating the saw, and an extensible work-supporting frame adapted to be extended from either end of the table, such frame comprising two parts adapted to be detachably connected, one part at each end of the table, and means by which the 20 two parts of the frame may be connected together to move as a unit or may be disconnected one from the other for use independently.

2. A stone-sawing machine comprising a work-supporting table, a saw, means for supporting the saw in position to act on the work, means for actuating the saw, and an extensible work-supporting frame adapted to be extended from either end of the table, such frame comprising two parts adapted to be detachably connected, one part at each end of the table, and means by which the 30 two parts of the frame may be connected together to move as a unit or may be disconnected one from the other for use independently, each part of the frame being provided with a work-supporting roller.

3. A stone-sawing machine comprising a work-supporting table, a saw, means for supporting the saw in position to act on the work, means for actuating the saw, elevating rollers for raising the work above the level of the table, and mechanism for raising the rollers above the surface of the table.

45 4. A stone-sawing machine comprising a work-supporting table having a saw-receiving groove therein, a saw, means for supporting the saw with its edge in the groove, means for actuating the saw, elevating rollers for raising the work above the surface of the table, and mechanism for raising the rollers to positions above the surface of the table.

50 5. A stone-sawing machine comprising a work-supporting table, a saw, means for supporting the saw in position to act on the

work, means for actuating the saw, elevating rollers for raising the work above the surface of the table, and eccentrics adapted and arranged to raise the rollers.

60

6. A stone-sawing machine comprising a work-supporting table, a saw, means for supporting the saw in position to act on the work, means for actuating the saw, elevating rollers for raising the work above the 65 surface of the table, levers carrying the rollers and adapted to raise the same, and eccentrics adapted to actuate the levers.

7. A stone-sawing machine comprising a work-supporting table, a saw, means for 70 supporting the saw in position to act on the work, means for actuating the saw, elevating rollers for raising the work above the surface of the table, levers carrying the rollers and adapted to raise the same, eccentrics for 75 actuating the levers, and other levers connected with the eccentrics to actuate the eccentrics.

8. A stone-sawing machine comprising a vertically adjustable frame provided with 80 ways, a carriage movable on the ways, a saw carried by the carriage, a vertically adjustable shaft hanger supported independently of the frame, a main shaft journaled in the shaft hanger, means for feeding the 85 carriage along the ways including a connection to the main shaft, means for actuating the saw including a connection to the main shaft, and means for concurrently vertically adjusting the frame and the shaft 90 hanger, whereby the connections of the saw-actuating means and of the carriage-feeding means with the main shaft are not disturbed by the adjustments of the frame.

9. A stone-sawing machine comprising a 95 vertically adjustable frame provided with ways, a tool-supporting carriage movable on the ways, a vertically adjustable shaft hanger supported independently of the frame, a main shaft journaled in the shaft 100 hanger, means for feeding the carriage along the ways including a connection with the main shaft, and means for concurrently vertically adjusting the frame and the shaft hanger.

105

In testimony whereof I have affixed my signature in presence of two witnesses.

WILLARD F. MEYERS.
